(57) **CLAIM**

The ornamental design for a hand brace, as shown and described.

DESCRIPTION

FIG. 1 is a front elevation view of a hand brace showing my new design with a second pad separated from a base pad and a strap attached thereto for clarity;
 FIG. 2 is a rear elevation view thereof;
 FIG. 3 is a right elevation view thereof;
 FIG. 4 is a left elevation view thereof;
 FIG. 5 is a top plan view thereof, the opposite side being a mirror image of the shown; and,
 FIG. 6 is an isometric view thereof.
